UNITED STATES PATENT OFFICE.

BENJAMIN T. ALLEN, OF HARRISBURG, PENNSYLVANIA, ASSIGNOR OF THREE-FOURTHS
TO CHRISTIAN W. LYNCH, WILLIAM JENNINGS, AND J. T. HAMBAY, ALL OF HARRIS-
BURG, PENNSYLVANIA.

STEAM ENGINE.

1,278,818.

Specification of Letters Patent. Patented Sept. 17, 1918.

Application filed April 6, 1917. Serial No. 160,289.

To all whom it may concern:

Be it known that I, BENJAMIN T. ALLEN, a citizen of the United States, residing at Harrisburg, in the county of Dauphin and State of Pennsylvania, have invented certain new and useful Improvements in Steam-Engines, and I do hereby declare the following to be a full, clear, and exact description of the same, reference being had to the accompanying drawings, forming part of this specification.

The present invention relates to steam engines, of that type wherein the exhaust ports are located at a point to be uncovered by the forward movement of the piston during the power stroke, and it has for its object to provide a construction whereby, during the return, compression or scavenging stroke, the steam trapped in the cylinder and undergoing compression will have a counterflow movement through the inlet ports and will be transferred from one side of the piston or end of the cylinder, to the opposite side of the piston or end of the cylinder, to thereby add to the capacity of the steam expanding during the working stroke after the inlet of live steam has been cut off, thus securing thermal efficiency and utilizing a portion of the heat and expansive force of the piston compressed steam which would otherwise be lost, with the result that a considerable economy in the consumption of steam is effected and a single cylinder engine may be made to operate with substantially the economy of a multiple cylinder engine operating on the compound principle.

Referring to the accompanying drawings,

Figure 1 is an elevation of an engine embodying the present invention.

Fig. 2 is a section in a horizontal plane through the cylinder, piston and valve chamber.

Figs. 3, 4, 5 and 6 are views substantially corresponding to Fig. 2, but showing the valve and piston in different positions assumed by them during a complete working stroke in one direction.

Fig. 7 is a section in a vertical transverse plane through the cylinder, valve chamber and transfer passage with the piston and valve omitted.

Fig. 8 is a detail section on an enlarged scale through the valve chamber and valve.

Fig. 9 is an elevation looking at one end 55 of the valve.

Fig. 10 is a diagrammatic view of an indicator card taken from an engine such as that illustrated in the drawings.

Like letters of reference in the several figures indicate the same parts.

The conventional arrangement of the parts of the engine illustrated embodies a base frame A, a crank shaft B, fly wheel C, automatic centrally balanced inertial governor 65 D, valve ram or slide E connected by a single eccentric rod with the inertia governor mechanism, and piston and valve rods F and G, respectively.

The main cylinder H and valve chest I are preferably arranged side by side parallel with each other and with the steam inlet and throttle valve K at the top and the exhaust outlet L at the bottom. The cylinder is provided with centrally arranged exhaust 70 ports l which communicate with an exhaust passage l' extending around the cylinder any preferred or desired distance. At each end the cylinder is provided with inlet and counterflow ports M, which conveniently communicate with small annular enlargements m, at the ends of the cylinder, and with annularly arranged ports m' in cylindrical bushings in the valve chamber I. The live steam from the boiler enters the central portion of the valve chamber through the inlet K and communicating with this central portion of the valve chamber are chambers N extending around the end portions of the cylinder, the chamber N' in the removable 80 cylinder head being in communication with the chamber N at that end through a duct or pipe N'.

The piston employed is of a construction whereby, when, at one end of its working 95 stroke the exhaust ports l will be opened, but with the working face of the piston in proximity thereto, while the opposite working face of the piston will be in such proximity to the further end of the cylinder as 100 to give only the necessary clearance volume at the end of the stroke. In engines as heretofore constructed, where counterflow has not been provided for, the compression runs up to such a degree that it is necessary to 105 provide a very large clearance volume at the end of the stroke. These clearance volumes interfere with the economy of the engine,

and in the present construction provision is made, whereby a counterflow of the steam during the compression stroke may take place into a suitable storage or transfer duct, such counterflow, however, being cut off at a point during the stroke of the engine at which it is desired to trap the steam remaining in the cylinder for final compression. The steam in the storage or transfer passage is admitted to the opposite end of the cylinder or on the opposite side of the piston and mixes with the steam which is already undergoing expansion to perform useful work on the piston until the central exhaust ports are opened by the forward movement of the piston. This cycle of operations is repeated in the reverse direction during the opposite movement of the piston.

The arrangement of the valve mechanism for controlling the admission of steam and for controlling the counterflow steam and for controlling the admission of the counterflow steam to the opposite side of the piston is preferably so constructed and proportioned that the counterflow steam will be compressed by the piston to a point which may approximately equal the pressure of the steam undergoing expansion at the instant when the compressed counterflow steam is admitted to the cylinder and commingles with the expanding steam.

In the preferred construction a valve mechanism competent to perform the several functions conveniently takes the form of a balanced piston valve, and it may embody means whereby the valve heads are made adjustable with relation to each other and each head embodies means whereby it may be adjusted to vary the time of cut off and admission of the counterflow steam with relation to the time of admission and cut off of the live steam.

The valve shown is of the piston type and embodies two heads indicated generally at O and O'. These two heads are so positioned on the valve rod G that they will properly coöperate with the ports m leading to the ends of the cylinders and at all times they divide the valve chamber into three compartments, namely, a central and two end compartments. The end compartments are in communication with each other through a transfer duct P, and said compartments, together with the transfer duct constitute what might be termed a compression transfer chamber in which the counterflow steam is compressed until such time as the valve may be moved to close the ports and to open the ports to the opposite end of the cylinder. In order that provision may be made for not only changing the relation or distance between the two valve pistons, so as to regulate the period of cut off of live steam, but also to regulate the period of cut off and opening of the ports

for the control of the counterflow compressed steam, the valve pistons are adjustably mounted on the valve rod, as, for example by locating the piston O' between adjustable abutments or lock nuts o', and by forming each valve piston in sections which are adjustable with relation to each other. A convenient and preferred arrangement is that shown in Fig. 8, where it will be seen that supplemental valve piston members O² are mounted on the main piston members and are adapted to be adjusted with relation thereto by tension and compression lock screws R and R', respectively. The two valve piston members are each preferably provided with the usual packing rings and the total width or thickness of each valve piston is preferably greater than the width of the ports longitudinally of the axis of the valve. Thus, the ports are closed to the live steam before being opened for the passage of counterflow steam and by adjusting the width or thickness of the valve the period during which the piston may be moved in the final compression of the steam in the cylinder and the timing of the opening of the ports at the opposite end of the cylinder for the admission of the compressed counterflow steam may be accurately regulated.

In the position shown in Fig. 2, the piston has reached the left hand extreme of its movement, the exhaust ports are opened to the right hand end of the cylinder and live steam is entering through the ports M at the left hand end of the cylinder. The valve is moving toward the left and continues to move toward the left, as shown in Fig. 3, while the piston advances. During this movement of the piston the ports at the right hand end of the cylinder are wide open to the compression transfer chamber and during the movement of the piston after the exhaust ports are closed steam from the right hand end of the cylinder counterflows into the transfer chamber. As shown in Fig. 4, the valve has begun its reverse movement and closes the ports at the left hand end of the cylinder, but the ports at the right hand end remain open and the steam on the working side of the piston begins to operate expansively, while steam at the right hand end is still free to counterflow into the transfer chamber. As shown in Fig. 5, the movements of the piston and valve continue, the ports at the right hand end are closed completely, after which the final compression takes place at this end of the cylinder, and the ports at the left hand end are opened to the transfer chamber, thus permitting the steam from the latter to flow in and commingle with the steam in the left hand end of the cylinder, thereby performing useful work. The movement in this direction continues until the parts assume the position shown in Fig. 6, and the exhaust

ports are opened when the parts assume the opposite position from that shown in Fig. 2 and the cycle of operations is continued in the reverse direction. From the foregoing it will be seen that the live steam entering the cylinder follows the piston until the reversal of the piston valve closes the ports. A short time after the closing of the ports through which live steam entered, the valve 5 opens, the ports at the opposite end of the cylinder admitting steam to that end which has been compressed by the piston into the transfer chamber. Before the piston completes its stroke, this transfer chamber is 10 cut off from the compression side of the piston and the remaining steam in the cylinder is finally compressed in the clearance space at the end of the cylinder.

The steam is preferably expanded from a 20 small clearance, about seven per cent. of the piston displacement, and on the return stroke the steam trapped in the cylinder and chamber is compressed to a volume equal to about fifty per cent. of the piston displacement. When the piston has moved about three-fourths of its stroke, the communication with the chamber is cut off and the steam left in the cylinder is compressed to the small clearance shown in Fig. 2.

30 Referring to the indicator card diagram, shown in Fig. 10, steam enters the cylinder at 1; the admission valve is closed at 2; at 3 the storage and transfer chamber is in communication with the cylinder, and the steam 35 in the chamber mixes with the expanding steam performing work on the piston. At 4 the central exhaust ports are opened and the steam escapes to the atmosphere until the piston reaches the end of its stroke and 40 again returns to approximately the point 5. Counterflow takes place to approximately the point 6, and final compression, from the point 6 to the point 1.

Obviously, the compression space may be 45 approximately fifty per cent. of the piston displacement, so that the exhaust line at the bottom of the indicator card rises very gradually until the piston reaches the point 3, at which time the communication with the 50 transfer chamber is cut off and the compression is completed in the relatively small clearance volume or space immediately back of the piston.

To prevent thermal losses it is preferred 55 that the cylinder, valve chest and transfer chamber be inclosed by a suitable jacket of non-conducting material, as shown at S, the non-conducting material being made to fill all the recesses in the exterior walls of the 60 cylinder between the projections formed by the steam and exhaust passages and chambers.

The engine is provided, as usual, with 65 drainage valves shown at T, in Fig. 1, which drainage valves lead from the bottom of the

cylinder at each end, serve to discharge any accumulations of water or condensation, and may be utilized in starting the engine in a way well understood by steam engineers.

What is claimed is:

1. In a steam engine, the combination with the cylinder having steam admission ports at its ends and exhaust ports intermediate the ends, a piston working in said cylinder between the admission ports and controlling the opening and closing of the exhaust ports when in proximity to the forward extremes of its movements, and a transfer chamber extending between the admission ports, of valve mechanism controlling the opening and closing of communication between the admission ports and transfer chamber, whereby counterflow steam from one end of the cylinder will be transferred and admitted to the opposite end of the cylinder. 70

2. In a steam engine, the combination with the cylinder having steam admission ports at its ends, exhaust ports intermediate the ends, a transfer chamber extending between the admission ports and a piston working in the cylinder between the admission ports and controlling the opening and closing of the exhaust ports when in proximity to the forward extremes of its movements, of a valve mechanism controlling both the admission of live steam to the admission ports and the flow of steam through the transfer chamber from one to the other of the admission ports. 90

3. In a steam engine, the combination with the cylinder having steam admission ports at the ends, exhaust ports intermediate the ends and a transfer chamber extending from one end to the other, of a piston working in the cylinder between the admission ports and controlling the opening and closing of the exhaust ports when in proximity to the forward extremes of its movements, and a valve mechanism controlling both the admission of live steam to the inlet ports and the flow of steam through the transfer passage from one end of the cylinder to the other. 100

4. In a steam engine, the combination with the cylinder having steam admission ports at the ends, exhaust ports intermediate the ends and a transfer chamber extending from one end to the other, of a piston working in the cylinder between the admission ports and controlling the opening and closing of the exhaust ports when in proximity to the forward extremes of its movements, a valve chamber between the admission ports, and a balanced valve controlling both the admission of steam to both ends and the transfer of steam from one end of the cylinder to the other through the transfer chamber. 115

5. In a steam engine, the combination with the cylinder having admission ports at the ends and exhaust ports at the center, a valve chamber between the admission ports and a 120

transfer passage connecting and formed in part by opposite ends of the valve chamber, of a piston controlling the opening and closing of the exhaust ports when in proximity to the forward extremes of its movements, and a balanced piston valve working in the valve chamber to control the communication of the inlet ports with the center and ends of the valve chamber, whereby live steam may be admitted to the cylinder and steam compressed by the piston transferred from one to the other of said admission ports.

6. In a steam engine as specified in claim 3, a balanced piston valve having sectional valve pistons with means for adjusting the sections axially of the valve to vary the thickness of the valves for controlling the relative time of opening and closing communication with the transfer passage.

7. In a steam engine as specified in claim 3, a balanced slide valve embodying pistons

adjustable toward and from each other to vary the admission and cut off to the cylinder.

8. In a steam engine as specified in claim 3, a balanced slide valve embodying sectional valve pistons adjustable toward and away from each other, and means for adjusting the sections axially of the valve to vary the thickness of the valves.

9. In a steam engine, the combination with a cylinder having steam admission ports at its ends, exhaust ports intermediate the ends, a transfer chamber extending between the admission ports and a piston working in the cylinder between the admission ports and controlling the opening and closing of the exhaust ports when in proximity to the forward extremes of its movements, of a valve mechanism controlling the admission of live steam to the cylinder and adjustably controlling the flow of steam from one to the other of the admission ports.

BENJ. T. ALLEN.
